DESIGN FOR A COMBINED COFFEE MEASURING AND DISPENSING DEVICE

John Kohl, Chicago, Ill.

Application March 25, 1933. Serial No. 47,586

Term of patent 3½ years

To all whom it may concern:

Be it known that I, JOHN KOHL, a citizen of the United States, residing at Chicago, in the county of Cook, State of Illinois, whose post office address is 3140 West 54th Place, Chicago, Illinois, have invented a new, original, and ornamental Design for a Combined Coffee Measuring and Dispensing Device, of which the following is a specification, reference being had to the accompanying drawing, forming a part thereof.

The cup depicted in the drawing forms a part of the design.

Fig. 1 is a front elevational view of the com-

bined coffee measuring and dispensing device showing my new design;

Fig. 2 is a side elevational view of the same; and

Fig. 3 is a top plan view of the same on a reduced scale.

I claim:
The ornamental design for a combined coffee measuring and dispensing device as shown and described.

Signed at Chicago, county of Cook, State of Illinois, this 22nd day of March, A. D. 1933.

JOHN KOHL.
